Primary Examiner — Bridget L Eland(74) *Attorney, Agent, or Firm* — Birchwood IP(57) **CLAIM**

The ornamental design for a WiFi extender, as shown and described.

DESCRIPTION

FIG. 1 is a front, right and top perspective view of a WiFi extender, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front, right and top perspective view of the WiFi extender in a use state; and,

FIG. 10 is a rear, left and bottom perspective view of the WiFi extender in a use state.

The broken lines shown in the drawings illustrate portions of the WiFi extender that form no part of the claimed design.
